UNITED STATES PATENT OFFICE.

GEORGE J. WINTER AND CHARLES S. DIEBOLT, OF BUFFALO, NEW YORK.

RESILIENT SHOE.

1,314,997.

Specification of Letters Patent.

Patented Sept. 2, 1919.

Application filed March 1, 1918. Serial No. 219,765.

To all whom it may concern:

Be it known that we, GEORGE J. WINTER and CHARLES S. DIEBOLT, citizens of the United States, residing in Buffalo, in the county of Erie and State of New York, have invented new and useful Improvements in Resilient Shoes, of which the following is a specification.

This invention relates to that class of shoes which are provided with means whereby the same are rendered waterproof and resilient and it is the object of this invention to provide a shoe of this character which is low in cost, capable of being easily manufactured and which will not only adapt itself to the conformation of the foot but also provide a resilient tread and protect the bottom of the foot from moisture and extremes of temperature.

20 In the accompanying drawings:

Figure 1 is a vertical longitudinal section of a shoe constructed in accordance with our invention. Fig. 2 is a bottom plan view of the intermediate or protecting layer of the shoe which is interposed between the outsole and the insole thereof. Fig. 3 is a cross section of the shoe taken on line 3—3, Fig. 1. Fig. 4 is a horizontal section taken on the correspondingly numbered line in

30 Fig. 1.

Similar characters of reference indicate corresponding parts throughout the several views.

The general construction of the shoe may be varied as to details inasmuch as our improvements are capable of use in shoes of various kinds. In the drawings our invention is shown applied to one form of shoe which is suitable for receiving our improvements and as there shown the same consists essentially of an upper 1, an insole 2 arranged below the upper, a shank piece 3 engaging with the under side of the instep or central part of the insole, and an outsole 4 arranged below the insole and shank piece. Along the marginal portion of the front part of the insole the same is provided with a welt 5 which is secured in accordance with the usual and well known Goodyear stitch 6

to the upper and insole so that the underside 50 of the insole is raised above the level of the underside of the welt.

One feature of our improved shoe consists in arranging a layer 7 of impervious material, such as rubber, between the upper 55 side of the outsole and the underside of the welt and the insole, this intermediate layer being secured at its margin to the welt and outsole in any suitable manner, for instance, by means of a marginal row of stitches 8, as 60 shown in Figs. 1, 2 and 3. This rubber layer therefore not only serves to cushion the underside of the shoe but also protects the foot against excessive coolness in the winter time and undue warmth in the summer time as well as preventing cracking of the insole.

Inasmuch as the underside of the front part of the insole is raised above the underside of the welt, an upper air space 9 is 70 formed between the insole and the intermediate protective layer at the front ends of these members which further cushions the step of the foot and retards the passage of moisture through the same from the underside of the shoe to the foot as well as protecting the foot from undue changes in temperature.

In order to still further increase the resilience of the shoe and protect against 80 dampness and temperature changes upon the underside thereof an additional air gap is formed between the underside of the protecting layer 7 and the upper side of the outsole. In its preferred construction this 85 air gap is divided into a front section or air space 10 which is arranged underneath the toe part of the shoe and a rear air space or section 11 which is arranged underneath the ball part of the shoe in front of the instep. 90 Thereof, these lower front and rear air spaces being separated by a transverse partition or rib 12 which is curved and adapted to register with the joint between the toes and the ball of the foot resting upon the sole or bottom of the shoe. By this means the top of the insole is capable of conforming more readily to the surface on the underside of

the foot, thereby rendering the shoe more comfortable in addition to yieldingly supporting the foot.

It will be noted that by the employment 5 of these additional air spaces on the under-side of the impervious intermediate layer air cushions are formed between the upper and lower sides of the layer and the insole and outsole above and below the same, there- 10 by obtaining the maximum cushioning effect for the foot on the front part of the shoe as well as guarding to the utmost degree against the transmission of any moisture or undue temperature through the front part 15 of the shoe bottom to the foot.

Another feature of our improved shoe resides in the construction of the heel so as to render the same resilient, easy to repair in case of wear and also to protect the rear 20 of foot resting thereon against undesirable temperature and moisture. As shown in Figs. 1 and 4, this improved heel comprises an elastic body which is arranged underneath the heel portion of the shoe bottom 25 and consists of a marginal upright wall 13 which engages its upper edge with the underside of the outsole, a horizontal flexible diaphragm 14 arranged within this wall be- 30 tween the upper and lower edges thereof and connected with the inner side of the same, an upper boss 15 arranged centrally on the upper side of the diaphragm and engaging with the underside of the outsole and a lower boss 16 arranged centrally on the un- 35 derside of the diaphragm and projecting downwardly therefrom. The wall, dia- phragm and bosses of this heel body may be constructed of any suitable resilient ma- 40 terial but preferably of rubber or a rubber composition. The heel body may be secured to the sole in any suitable manner, for in- 45 stance, by means of upright nails 17 which pass through the body of the heel and en- gage the heads at their lower ends with metal anchor disks 18 which are molded in 50 the heel body while the upper ends of these nails engage with adjacent parts of the shoe bottom.

The underside of this heel body is engaged 55 by a lift 19, preferably of leather or other suitable material, which is adapted to take the wear and can be renewed from time to time when worn out. This lift engages its marginal part with the lower edge of the heel wall while the central part thereof en- 60 gages its upper side with the lower end of the lower boss, as clearly shown in Fig. 1. Although various means may be employed for securing this lift detachably to the heel body and shoe bottom the preferred means for this purpose which are shown in the drawings comprise a plurality of nails 20 passing upwardly through this lift, the heel

body and the shoe bottom and arranged out of line with the nails which secure the heel body to the shoe bottom, thereby permitting of removing and renewing the lift without disturbing the heel body. 65

The upper end of the upper boss projects slightly above the top of the heel wall when this body is removed from the shoe bottom whereby upon applying this body to the shoe bottom the diaphragm will be deflected downwardly slightly and in a partly flexed condition when the heel is in place, thereby 70 insuring a resilient support for the heel of the foot. 75

In this form of heel the flexible dia- phragm together with the air spaces 21, 22 formed between opposite sides of the same 80 and the sole and lift together form a cushion support for the heel and enables heel pressure to be elastically supported while walking, while at the same time retaining sufficient firmness in the heel due to the solid 85 portions provided by the bosses and the walls of the heel body which insure firmness in the step.

Our improved cushioning and protecting means can be produced by the use of com- 90 paratively low priced molds and the same can be applied to shoes now in general use without requiring any special skill for this purpose, thereby enabling these improve- 95 ments to be incorporated in a shoe without undue added cost.

By reason of the elastic layer between the insole and outsole and the elastic heel body the outsole and lift are caused to wear more evenly and they also prevent excessive per- 100 spiration of the foot. The arch of the foot is also properly supported and pressure on the joints is relieved. Furthermore a shoe constructed in accordance with our invention will not produce any disagreeable squeaking 105 while in use, the same is absolutely watertight and in addition is a safeguard against electric shocks for the person wearing the shoe inasmuch as the rubber portions there- 110 of serve as insulating members which prevent the passage of an electric current through the shoe.

We claim as our invention:

1. In a shoe, the combination of a sole, and a heel body of rubber secured to the 115 underside of said sole and comprising a marginal wall, a horizontal diaphragm ar- ranged within said wall between the upper and lower edges thereof and connected at its edge with the inner side of said wall and 120 a boss arranged centrally on the upper side of said diaphragm and engaging with the underside of said sole, said diaphragm being flexed downwardly from its normal position by engagement of said wall and boss with 125 said sole.

2. In a shoe, the combination of a sole, and a heel body of rubber secured to the underside of said sole and comprising a marginal wall, a horizontal diaphragm arranged within said wall between the upper and lower edges thereof and connected at its edge with the inner side of said wall, an upper boss arranged centrally on the upper side of said diaphragm and engaging with 5 the underside of said insole, and a lower boss arranged centrally on the underside of said diaphragm, said diaphragm being flexed downwardly by engagement of said wall and upper boss with said sole, and a lift secured to the underside of said heel body and engaging its marginal part with 15 said wall and its central part with said lower boss.

GEORGE J. WINTER.
CHARLES S. DIEBOLT.
